UNITED STATES PATENT OFFICE.

WILLIAM L. GILE, OF MUSKEGON, MICHIGAN.

COMPOSITION PACKING.

SPECIFICATION forming part of Letters Patent No. 763,277, dated June 21, 1904.

Application filed February 12, 1904. Serial No. 193,347. (No specimens.)

To all whom it may concern:

Be it known that I, WILLIAM L. GILE, a citizen of the United States, residing at Muskegon, in the county of Muskegon and State of Michigan, have invented new and useful Improvements in a Composition of Matter for Packing, of which the following is a specification.

This invention relates to a new and useful composition of matter used in forming packing for pistons of steam-engines and other places where the steam and air tight packing is desirable.

It also relates to a completed packing composed of the ingredients and constructed in the manner hereinafter described.

To more clearly illustrate the packing, reference is had to the accompanying drawings, in which—

20 Figure 1 is an elevation, partly broken away, of a packing-ring constructed in accordance with this invention; and Fig. 2 is a cross-section of the ring.

This composition of matter consists of the following ingredients prepared and combined in substantially the same proportions stated, to wit: antimony, five parts; tin, twenty parts; lead, sixty-seven and one-half parts; asbestos, five parts; graphite, two and one-half parts. 30 The lead, tin, and antimony are first melted together and about one-third of the same is cut into strips, while the balance is prepared in solid globules, preferably of varying sizes. The asbestos is shredded, and the graphite is prepared in small particles of any suitable shape. The ingredients above described are then thoroughly mixed together, so as to form a heterogeneous mass.

The composition, composed of substantially the portions and prepared in substantially the forms above described, is placed in molds or formers and subjected to a high pressure, so as to be formed into rings or shapes adapted to fit the different-sized pistons to which the same are to be applied. The rings or formed-up portions of packing are then in suitable forms to be used and may be packed and shipped as a complete article of manufacture.

The preparation and article above described is adapted for use in connection with steam-

engines, more especially where the packing is subjected to heat from steam or other heating material, and the rings thus constructed contain sufficient elasticity or mobility to adapt themselves to the places where they are to be applied and to furnish an absolute steam-tight joint. The said packing may be used for packing valve-stems. In fact, it may be used in all places where a tight packing is required where the same is subject to steam- 60 pressure or other pressure of like quality.

Referring to the drawings by reference characters, A denotes the inside of the packing, and B the periphery; C, the metallic globules or pellets of varying sizes; D, the flexible metallic strips cut in the form of thin ribbons; E, shredded asbestos, and F the graphite.

Having thus described my invention, what I claim to have invented, and desire to secure by Letters Patent of the United States, is— 70

1. A molded heterogeneous packing-ring consisting of antimony, tin and lead combined in the form of flexible binder-strips, antimony, tin and lead combined in the form of metallic globules, shredded asbestos, and a lubricant. 75

2. A molded heterogeneous packing-ring consisting of antimony, tin and lead combined in the form of flexible binder-strips, antimony, tin and lead combined in the form of metallic globules of varying sizes, shredded asbestos, 80 and a lubricant.

3. As a new article of manufacture, a molded and compressed heterogeneous packing consisting of metallic globules, metallic flexible binder-strips in the form of ribbons, shredded asbestos, and graphite in small particles. 85

4. As a new article of manufacture, a molded and compressed heterogeneous packing consisting of metallic globules of varying sizes, metallic flexible binder-strips in the form of ribbons, shredded asbestos, and graphite in small particles. 90

In testimony whereof I have hereunto set my hand in presence of two subscribing witnesses.

WILLIAM L. GILE.
